UNITED STATES PATENT OFFICE.

HENRY F. SCHMIDT, OF PITTSBURGH, PENNSYLVANIA, ASSIGNOR TO WESTINGHOUSE ELECTRIC & MANUFACTURING CO., A CORPORATION OF PENNSYLVANIA.

FLUID-TRANSLATING DEVICE.

1,386,958.

Specification of Letters Patent. Patented Aug. 9, 1921.

Application filed September 12, 1919. Serial No. 323,307.

To all whom it may concern:

Be it known that I, HENRY F. SCHMIDT, a citizen of the United States, and a resident of Pittsburgh, in the county of Allegheny and State of Pennsylvania, have made a new and useful Invention in Fluid-Translating Devices, of which the following is a specification.

This invention relates to fluid translating devices and particularly to means for ejecting liquid of condensation from a condenser.

Where ejectors are employed to discharge condensate from a condenser some difficulty is encountered, due to the fact that the condensate is hot, unless the condensate is delivered to the ejector under considerable head. For the same reason it is difficult to produce a self-starting ejector which is reliable in operation.

An object of my invention is to produce a new and improved ejector which is self-starting and is capable of efficiently and effectively entraining and discharging relatively hot condensate from a condenser.

A further object is to produce a new and improved condensate ejector which is simpler and more compact than other condensate ejectors heretofore known.

A further object is to produce a combined condenser and ejector in which means are employed for improving the operation of the ejector and at the same time simplifying and making the combination compact.

These and other objects which will be made apparent throughout the further description of my invention are attained by means of the apparatus embodying the features herein described and illustrated in the drawing accompanying and forming a part hereof.

The drawing is a diagrammatic sectional view of a condensate ejector embodying my invention, and shown in connection with a diagrammatic sectional view of a condenser.

The condenser 5 is provided at its bottom with a hot well 6, in which condensate collects. Extending through the hot well 6, I have shown an ejector 7 for entraining and ejecting the condensate. As illustrated, the ejector is provided with a nozzle 8, which extends through one wall of the hot well 6 and is adapted to discharge motive fluid at high velocity into and through four combining cones 9, 10, 11 and 12 which, as

shown, are axially aligned with the nozzle 8 and are located within the hot well. I have also shown a diffuser 13 axially aligned with the nozzle 8 and the combining cones, and extending through the opposite wall of the hot well 6, so that its discharge is exposed to atmospheric pressure or at least to a pressure greater than that existing in the condenser.

As illustrated, the combining cones 9, 10, 11 and 12 are mounted in diaphragms 14, 15, 16 and 17, which I have shown extending across the hot well 6 at right angles to the axis of the ejector 7 and dividing the hot well into compartments, each of which is open at the top. By means of these diaphragms or baffles, condensate is prevented from circulating locally, that is, it cannot flow from the outlet of a combining cone back to the inlet of the same or any other cone without going up and over one of the diaphragms and thereby being mixed with cool condensate and being further cooled by evaporation. As illustrated, the spacing between combining cones 9, 10, 11 and 12 progressively increases, the cone 9 extends beyond the inlet edge of the cone 10 whereas a gap separates the last two cones 11 and 12 and the last cone 12 from the diffuser 13. In the apparatus illustrated the first two cones 9 and 10 are primarily designed to facilitate entraining the condensate and the last two, 11 and 12, for permitting overflow at starting up. However, it will be understood that, in the various stages of operation, any or all of the combining cones may act as entraining or overflow cones.

In operation motive fluid is discharged at high velocity through the nozzle 8 and into and through the combining cones 9, 10, 11 and 12. Condensate is entrained by the jet of motive fluid and is carried by it into and through the cones and the diffuser 13, in a well known manner. At the time of starting the condensate is at rest and an interval of time must elapse before a column of water having sufficient velocity to discharge itself from the condenser is established. During this interval the space between the combining cones or between the last cone 12 and the diffuser function as overflow outlets. It is more probable that at the instant of starting up the first cone 9 would act as an entraining cone whereas the others would act as overflows.

During normal operation all of the combining cones may act as entraining cones, and for this reason the ejector is capable of operating with hotter condensate than is possible with an ordinary ejector. It is evident that during normal operation the hot well 6 serves as a common inlet chamber for all of the combining cones of the ejector.

While I have described and illustrated but 10 one embodiment of my invention, it will be apparent to those skilled in the art that various changes, modifications, additions and omissions may be made in the apparatus described and illustrated without departing 15 from the spirit and scope of the invention as set forth by the appended claims.

What I claim is:

1. In combination with a condenser and its hot well, an ejector comprising a motive 20 fluid delivery nozzle, a combining cone, the inlet of which is in open communication with the hot well and a diffuser alined with said cone and having its inlet in open communication with the hot well and its discharge subjected to a pressure greater than 25 that existing in the condenser.

2. In combination with a condenser and its hot well, an ejector comprising a motive 30 fluid delivery nozzle, a combining cone, located within the hot well, and adapted to receive motive fluid delivered by said nozzle, a diffuser having its inlet located within the hot well and in open communication therewith and its outlet subjected to a pressure 35 greater than that within the condenser and a partition located within the hot well and forming a deflecting baffle between the inlet and the discharge of said cone.

3. The combination with a condenser and 40 its hot well, an ejector comprising a fluid delivery nozzle, a plurality of alined cones alined with said nozzle, and a diffuser alined with said cones characterized by that the nozzle projects into the hot well, the inlet 45 and outlet of each cone is in open communication with the hot well and the inlet to the diffuser is in open communication with the hot well.

4. In combination with a condenser and 50 its hot well, an ejector having its combining chamber located within and in open communication with the hot well, and means located within the hot well for deflecting overflow from the hot well upwardly toward the 55 surface of the condensate contained in the hot well.

5. In combination with a condenser and its hot well, an ejector comprising a motive 60 fluid delivery nozzle, having its outlet located within the hot well at a point below the normal water level, a combining cone located in the hot well, and having its inlet and outlet in open communication with the interior of the hot well, a diffuser alined 65 with said cone and having its inlet in open

communication with the hot well and means within the hot well for deflecting overflow streams issuing from said cone so that heated water issuing therefrom is subjected to cooling before reentering the cone.

6. In combination with a condenser having a condensate outlet, a condensate ejector having its inlet and overflow in direct communication with the condensate outlet and means for causing condensate from the overflow to pass up into the condenser outlet before being reentrained at the inlet of the ejector.

7. In an ejector, a nozzle, a plurality of combining cones whose inlet and outlet ends 80 communicate with a single chamber, in which cones fluids are entrained during one stage of operation and from which cones fluids overflow during another stage of operation, and a diffuser into which the combining cones discharge.

8. In an ejector, a nozzle, a plurality of combining cones spaced progressively farther apart, and a diffuser into which the combining cones discharge.

9. In combination with a condenser, a hot well, an ejector having a plurality of combining cones in direct communication with the hot well, means for delivering motive fluid to the combining cones at high velocity, 95 and a diffuser for receiving the fluids discharged from the combining cones.

10. In combination with a condenser, a hot well, a plurality of combining cones directly communicating therewith, some of 100 said cones being spaced farther apart than others, a diffuser into which the combining cones discharge; and a nozzle for delivering fluid to the combining cones at high velocity.

11. In combination with a condenser, a hot well, a plurality of combining cones axially alined and directly communicating with the hot well, a nozzle for delivering motive fluid to the combining cones, a diffuser axially alined with the combining 110 cones, and means for preventing fluid discharged from a combining cone from passing back directly to reenter said cone.

12. An ejector having a nozzle, a plurality of combining cones, a diffuser, and a common inlet and overflow chamber, for said combining cones.

13. An ejector having a nozzle, a combining cone having a plurality of entraining and overflow ports, a diffuser, and a common inlet and overflow chamber for the several entraining and overflow ports of the combining cone.

14. An ejector having an overflow port and an entraining port, a common overflow 125 and inlet chamber for said ports and means whereby the fluids discharged from the overflow port are cooled before being entrained at the entraining port.

15. In an ejector, a nozzle, a combining

tube having entraining and overflow ports, a diffuser into which the combining tube discharges and means for cooling fluids discharged from the overflow ports before said

5 fluids enter the entraining ports.

16. In combination with a condenser, a hot well, an ejector having entraining and overflow ports directly communicating with the hot well in such a manner that said hot

well acts as a common inlet and overflow 10 chamber for the ejector and means for preventing local circulation between the overflow and entraining ports.

In testimony whereof I have hereunto subscribed my name this 11th day of Sep 15 tember, 1919.

HENRY F. SCHMIDT.
